(74) Attorney, Agent, or Firm — Cislo & Thomas, LLP

(57) CLAIM

I claim the ornamental design for eyes for plush toys, as shown and described herein.

DESCRIPTION

FIG. 1. Is a perspective view of my eyes for plush toys design;

FIG. 2. Is a front view thereof;

FIG. 3. Is a rear view thereof;

FIG. 4. Is a left side view thereof;

FIG. 5. Is a right side view thereof;

FIG. 6. Is a top view thereof; and,

FIG. 7. Is a bottom view thereof.

The broken lines in the drawings show environment that forms no part of the claimed design.

1 Claim, 4 Drawing Sheets
